Primary Examiner — Susan Bennett Hattan*Assistant Examiner* — Marie Fast Horse(74) *Attorney, Agent, or Firm* — Thompson Hine LLP(57) **CLAIM**

The ornamental design for a microphone box with dome shaped cap, as shown and described.

DESCRIPTION

FIG. 1 is a side, perspective view of a microphone box with dome shaped cap, shown with dome shaped cap in place;

FIG. 2 is a side view of the microphone box of FIG. 1;

FIG. 3 is a bottom, perspective view thereof;

FIG. 4 is a top view thereof;

FIG. 5 is a side, perspective view of the microphone box of FIG. 1 with the dome shaped cap removed; and,

FIG. 6 is a side view of the microphone box of FIG. 5.
